(57) **CLAIM**

The ornamental design for an electrical connector, as shown and described.

DESCRIPTION

FIG. 1 is a front elevation view of the electrical connector according to the present invention;

FIG. 2 is a rear elevation view of the electrical connector of FIG. 1;

FIG. 3 is a right side elevation view of the electrical connector of FIG. 1;

FIG. 4 is a left side elevation view of the electrical connector of FIG. 1;

FIG. 5 is a top plane view of the electrical connector of FIG. 1;

FIG. 6 is a bottom plan view of the electrical connector of FIG. 1; and,

FIG. 7 is a perspective view of the electrical connector of FIG. 1.
